UNITED STATES PATENT OFFICE.

FRANK G. HOLLAND, OF CLEVELAND, OHIO, ASSIGNEE OF ONE-HALF TO JOHN GREEN,
OF CLEVELAND, OHIO.

OIL PUMP.

Application filed April 23, 1925. Serial No. 25,239.

This invention relates to a measuring pump and more particularly to a pump having a cylindrical chamber with an oscillating piston therein and designed to discharge 5 a measured quantity of liquid upon each stroke of the piston.

The present invention has for an object to provide a measuring pump of the oscillating piston type in which the piston chamber forms a container which will retain, 10 without leakage a pre-determined quantity of liquid during periods in which the pump is not in use and which will discharge a pre-determined quantity of liquid upon each 15 stroke of the piston.

A further object is to provide a pump of the character referred to which is of a durable construction, which is reliable in operation, which has few parts and in which the 20 parts are so formed that they can be cheaply manufactured and assembled.

With the above and other objects in view the invention may be said to comprise the pump as illustrated in the accompanying 25 drawing hereinafter described and particularly set forth in the appended claims together with such variations and modifications thereof that will be apparent to one skilled in the art to which the invention 30 appertains.

Reference should be had to the accompanying drawings forming a part of this specification in which Fig. 1 is a side elevation, the inlet portion below the cylinder being 35 broken away and shown in section.

Fig. 2 is a vertical section shown on line 2-2 of Fig. 3. Fig. 3 is a top plan view of the body portion of the pump case. Fig. 4 is a side elevation of the pump looking toward the left in Fig. 1. Fig. 5 is a detail sectional view showing the packing by which the fluid tight engagement is provided between the piston and cylinder and between the partition member and piston shaft, Fig. 45 6 is a top plan view of the partition member. Fig. 7 is an end elevation of the partition member and piston. Figs. 8 and 9 are end and side elevations respectively of the casting from which the partition members are 50 made. Fig. 10 is a perspective view of the gauge for the check valve balls controlling the outlet openings. Fig. 11 is a fragmental detail view showing the inner end portion of the hand crank in side elevation.

55 Referring to the accompanying drawings,

the body portion of the pump casing is in the form of a casting which is provided with a transverse cylindrical bore 2, which forms the pump chamber. Beneath the bore 2 the casting has an integral tubular extension 3, 60 which is internally threaded at 4 to receive the upper end of an inlet pipe 5. Branch passages 6 extended from the threaded portion 4 around opposite sides of the bore 2, the passages 6 adjacent the upper end of the 65 casting having valve seats 7, and valve chambers 8, formed therein above the valve seats. Balls 9 are placed within the chambers 8 and are adapted to rest upon the seat 7 to close the passages 6, openings being provided in the upper end of the casting to permit an insertion of the balls into the chambers 8, these openings being closed by threaded plugs 10. Openings 11 are formed from the upper portions of the chambers 8 into 75 the bore 2 so that the liquid may flow past either check 9 from the inlet pipe 5 to the interior of the pump cylinder.

In forming the casting, the bore 2, the tube 3, the passages 6, the seats 7, the chambers 8 and the openings 11 are formed by 80 suitable cores in the mold. The bore 2 is then machined and the valve seat 7 may also be machined by suitable tools inserted through the openings in the top of the casting which are closed by the plugs 11.

The casting 1, at the top thereof, is formed with an annular boss 12 which is bored and tapped at intervals as shown at 13 in Fig. 2 to receive the tap bolts by which 90 the base flange of the discharge conduit 14 may be secured upon the top surface of the boss 12. Centrally of the annular boss 12 there is an upwardly projecting boss 15 and in the annular space between the boss 15 and the annular boss 12, outlet openings 16 are provided to the interior of the cylinder, the outlet openings 16 being controlled by suitable check valve balls 17.

The ends of the cylinder are closed by 100 front and rear heads 18 and 19 in which the piston shaft 20 is journalled. The shaft 20 extends through the front head 18, the head 18 being provided with an outwardly projection boss 21 through which the shaft extends, and a gland 22 being provided at the outer end of the boss to prevent leakage of the liquid along the shaft. A suitable hand crank 23 is fixed to the outer end of the shaft 20 and the boss 21 is provided at the 105 110

top thereof with radial flanges 24 and 25 which are in the path of the movement of the projecting part 26 of the crank 23.

The flanges 24 and 25 serve to limit the angular movement of the piston and one of these flanges is provided with a set screw 27 which may be adjusted to regulate the extent of the movement of the piston and thereby regulate the quantity of liquid discharge upon each stroke of the pistons.

In order to provide means for locking the hand crank against actuation one of the flanges and part 26 of the crank may be provided with openings 24^a and 26^a which register when the part 26 is in engagement with the flange and are adapted to receive a hasp of a padlock.

Between the upper portion of the cylinder and the piston shaft 20 there is provided a partition member 28 which is substantially T shaped in cross section having a web 29 and a head portion with side flanges 30. The head portion of the partition member fits the inner surface of the cylinder and the inner edge of the web 29 fits the cylindrical surface of the shaft 20. Openings 31 are provided through the flanges 30 of the head and these openings are adapted to register with the discharge openings 16 of the cylinder. The partition member is secured in place within the cylinder by means of a bolt 33 extending downwardly through the central boss 15, in the top of the casting and into the partition member 28 at the center thereof. The bolt 33 also serves to hold a sheet metal cage 34 for retaining the check valve balls 17, the cage 34 consisting of a flat sheet metal plate clamped upon the upper end of the boss 15 by the head of the bolt 33 and having side flanges 35 which extend downwardly on opposite sides of each of the balls.

At the inner ends of the web 29, the sides thereof taper inwardly and lie in radial planes and the outer edges of the flanges 30 lie in the same radial planes as the tapered sides of the web. The partition member 28 is in the form of a sector of a cylindrical annulus having a bearing surface 37 at the inner edge of the web which is of the same angular extent as the bearing surface of the head engaging the cylinder wall. The web 29 has a longitudinally extending slot 38 in which is mounted packing strip 39 which engages the piston shaft 20 throughout the length of the cylinder, the packing being pressed against the shaft by means of an arched spring 40 interposed between the bottom of the slot 38 and the inner edge of the packing strip. The partition member 28 is of the same length as the cylinder and fits between the heads 18 and 19 the ends of the partition member 28 being provided with grooves 41 adapted to receive the packing strips against which the

heads 18 and 19 are clamped to prevent leakage of liquid past the ends of the partition members.

It is exceedingly difficult to accurately machine a segment of a cylindrical surface and the configuration of the partition member 28 which has the form of a sector of cylindrical annulus is quite important, since a number of such partition members may be cut from a cylindrical casting in which the cylindrical surfaces have been machined prior to the cutting up of the casting to form the partition members. Figs. 8 and 9 of the drawing show a cylindrical casting 42 from which four of the partition members may be cut. The casting 42 is cored to provide triangular openings 43 extending endwise through the same and with an axial opening 44 which has radially projecting slots which form the packing grooves 38. The casting 42 is also cored to provide the openings 31 through the heads of the partition members and the packing grooves 41 at the ends thereof. Each quarter of the casting 42 forms one partition member 28 the webs 29 being formed between adjacent openings 43 and the casting being cut along diametrical planes which extend centrally through the openings 43 to provide flanges 30 extending in opposite directions from the web. The outer cylindrical surface of the casting 42 can be readily turned to the exact diameter of the cylinder and the central opening 44 can be easily machined to a size such that the piston shaft 20 will have a tight fit therein.

The piston shaft 20 has fixed thereto a vane 45 which has a close fit within the peripheral and end walls of the pump chamber. The vane 45 is secured within a radial slot 46 cut in the shaft 20 by means of a transverse rivet 47. The vane 45 has a body portion formed of a thick flat plate 48 to the opposite faces of which are attached thin plates 49 which are of greater width and length than the plate 48 and project behind the outer and side edges of said plate forming a groove along the outer and side edges of the vane adapted to receive the packing strips. Within this groove L shaped packing strips 50 are mounted, these strips being arranged in pairs side by side with one arm of the L extending along a side of the vane and the other arm extending along the outer edge of the vane. The arms of the strips of the two pairs which extend along the outer edge of the vane are of different lengths and the inner ends of the arms of the two pairs abut at offset points between the opposite ends of the vane, the abutting ends of the strips being stepped to provide shouldered joints 51 and 52.

The body plate 48 is provided with notches 53 in the opposite side and outer

edges thereof and in these notches are mounted coil springs 54 which bear against the inner sides of the packing strips to press the strips firmly against the peripheral and 5 end walls of the pump chamber.

In the operation of the pump a hand crank 23 is operated first in one direction and then the other through the full angular distance permitted by the stop members 10 with which the part 26 of the crank engages. These movements of the crank 23 cause the vane 48 to be shifted from a position adjacent one side of the partition member 28, to a position adjacent the opposite 15 side of the partition and reversely to the original position mentioned as the crank 23 is turned back and forth. In Fig. 2 of the drawing the arrows indicate the direction 20 of flow of liquid when the piston is being moved toward the right, this movement causing a partial vacuum to be created at the left of the piston so that atmospheric pressure forces the liquid to flow through the inlet pipe 5 which extends into a body 25 of liquid in a container upwardly through the left hand passage 6, raising the check valve 9 and flowing into the cylinder through the inlet opening 11. At the same time pressure is exerted upon the liquid at 30 the right of the piston causing the liquid to flow through the outlet opening 16 on the right hand side of the partition 28 into the discharge conduit 14 past the check valve 17, the check valve 9 in the right hand 35 passage 6 being held to its seat by pressure within the chamber 8.

Upon each stroke of the piston the contents of the cylinder is discharged into the discharge conduit and at the same time a 40 fresh charge of liquid is drawn into the cylinder through the inlet on the side opposite that from which the liquid is being discharged.

An important feature of the invention is the location of both the inlet and outlet openings in the upper portion of the chamber so that the pump chamber forms a container which will retain a full charge during periods in which the pump is not in use, 45 there being no valves through which the liquid in the chamber below the openings 11 may leak from the chamber back into the inlet pipe.

Having described my invention, I claim:

1. A measuring pump comprising a cylindrical pump chamber having an oscillatory piston therein and means cooperating with the piston to prevent passage of liquid from one side of the piston to the other, said chamber having valve controlled inlet and outlet passages in the upper portion thereof whereby said chamber forms a container adapted to retain without leakage a predetermined quantity of liquid, a handle for operating the piston, and an adjustable stop 50 for varying the stroke of the piston to regulate the quantity of liquid discharged.

2. A measuring pump comprising a cylindrical pump chamber having an oscillatory piston therein and means cooperating with the piston to prevent passage of liquid from one side of the piston to the other, said chamber having valve controlled inlet and outlet passages in the upper portion thereof whereby said chamber forms a container 55 adapted to retain without leakage a predetermined quantity of liquid, a handle secured to the piston and angularly spaced stop members in the path of movement of a part of the handle to limit the movement of the piston in both directions, one of said stop members being adjustable to vary the stroke of the piston.

3. A measuring pump comprising a horizontally disposed cylindrical pump chamber having an oscillatory piston therein comprising a shaft at the axis of the cylinder and a vane carried by the shaft and having a packing along the outer and end edges thereof to provide a fluid tight engagement 60 with the walls of the pump chamber, a partition member fixed to the cylinder above the shaft and having a fluid tight engagement with the walls of the chamber and with said shaft, said partition member having a packing strip along its inner edge engaging said shaft, said pump chamber having inlet and outlet passages communicating therewith adjacent the top thereof and on each side of the partition valves controlling the passages, and means for operating the shaft to discharge the contents of the chamber.

4. A measuring pump comprising a horizontally disposed cylindrical pump chamber having an oscillatory piston therein comprising a shaft at the axis of the cylinder and a vane carried by the shaft and having a packing along the outer and end edges thereof to provide a fluid tight engagement 65 with the walls of the pump chamber, a partition member fixed to the cylinder above the shaft and having a fluid tight engagement with the walls of the chamber and with said shaft, said partition member having a packing strip along its inner edge engaging said shaft, said chamber having inlet and outlet openings adjacent the top thereof on opposite sides of the partition, 70 an inlet conduit having passages extending communicating with said inlet openings, a discharge conduit with which said outlet openings communicate, check valves controlling said inlet passages, check valves controlling said outlet openings, and a handle secured to said shaft.

5. A measuring pump comprising a casting having a body portion in the form of a casting having a cylindrical bore extending transversely therethrough, said casting hav- 75 80 85 90 95 100 105 110 115 120 125 130

ing a tubular extension forming an inlet conduit at its lower end and passages extending from the inlet around the bore on opposite sides thereof communicating with the bore in the two upper quadrants thereof, said casting having provisions at its upper end for attachment of a discharge conduit, and discharge openings adjacent the inlet openings and adapted to communicate with the outlet conduit, heads closing the opposite ends of the bore, an oscillating piston comprising a shaft journaled centrally in the heads and projecting beyond one of them and a vane secured to the shaft and having packing strips engaging the cylindrical wall and heads of the casing to provide a fluid tight engagement with the heads and bore, a partition member secured to the casting within the bore between the top thereof and the shaft, said partition member having a fluid tight engagement with the heads and cylindrical wall of the chamber, a packing strip carried by the partition member and engaging the shaft, and check valves controlling the inlet passages and outlet openings.

6. In an oscillating piston pump, a piston comprising a shaft having a vane secured thereto said vane having a groove along its outer edge and along its side edges, L shaped packing strips fitting in said groove, said strips having arms extending along the sides of the vane to the shaft and arms extending along the outer edge thereof, said last mentioned arms having stepped ends which abut, and springs interposed between the body of the vane and the inner edges of the packing strips at the sides and at the outer edges of the vane.

40 7. In an oscillating piston pump, a piston comprising a shaft having a longitudinal groove, a vane having its inner end seated in said groove and fixed to the shaft, said vane having a flat body portion and flat plates secured to opposite faces of the body portion and projecting beyond the side and outer edges thereof to provide a packing groove, two pairs of L shaped packing strips arranged side by side in the groove, one pair having arms extending along one side edge of the vane and arms of different lengths extending along the outer edge thereof, the other pair of packing strips having arms extending along the opposite side edge of the vane and arms extending along the outer edge thereof and abutting the ends of the first mentioned strips, and springs interposed between the side and outer edges of the body portion and the inner edges of the strips.

60 8. A partition member for the cylinder of a pump of the oscillating piston type comprising a substantially T shaped member having a flanged head the outer surface of which is machined to fit within a cylindrical surface and a web, the inner edge of which

is machined to fit the cylindrical surface of a shaft, said web being slotted along its inner bearing edge to receive a packing strip, said web at the inner end thereof having tapering sides lying in radial planes and the flanges of the head having edges in the planes of said tapering sides, the flanges of the head having openings adapted to register with discharge opening through the cylinder wall.

9. A partition member for the cylinder of a pump of the oscillatory piston type comprising a member in the form of a sector of a cylindrical annulus, the outer surface of said member being adapted to conform to the inner surface of the cylinder and the inner surface thereof being adapted to conform to the surface of the piston shaft, the sides of said member being recessed to provide an outer flanged head and an inwardly projecting web.

10. A measuring pump comprising a cylindrical pump chamber, a shaft extending axially through the chamber, a partition member having a fluid tight engagement with the cylindrical and end walls of the chamber, said partition member having a groove along its inner edge, a packing strip in said groove, means for yieldingly pressing said strip against the shaft, a vane carried by said shaft, said vane having its outer and end edges grooved, packing in the grooved edges of said vane, means for yieldingly pressing said packing into engagement with the cylindrical and end walls of the chamber, and valve controlled inlet and outlet passages communicating with said chamber on opposite sides of the partition member and adjacent thereto.

11. A measuring pump comprising a cylindrical pump chamber, heads closing the ends of the chamber, a shaft extending axially through the chamber and journaled in the heads, said shaft having a groove extending longitudinally thereof, a partition member having a fluid tight engagement with the cylindrical wall and heads, said partition member having a groove along its inner edge, a packing strip in said groove, a spring in the groove for pressing said packing strip against the shaft, a vane secured in the groove of said shaft and having its outer and end edges in proximity to the cylindrical wall and heads of the chamber, the outer and side edges of said vane being grooved, packing strips in the groove of said vane, said strips at the side edges of the vane extending into the groove of the shaft, springs for pressing said strips toward the cylindrical wall and heads, and valve controlled inlet and outlet passages communicating with said chamber on opposite sides of the partition member and adjacent thereto.

12. In an oscillating piston pump, a piston comprising a shaft having a longitudinal groove, a vane having its inner end seated in

said groove and fixed to the shaft, said vane having a groove extending along the outer edge and along the side edges thereof, L shaped packing strips fitting in said groove, said strips having arms extending along the sides of the vane into the groove of the shaft, and arms extending along the outer edges of the vane, said last mentioned arms hav-

ing stepped ends which abut, and springs interposed between the body of the vane and 10 the inner edges of the packing strips at the sides and at the outer edges of the vane.

In testimony whereof, I hereunto affix my signature.

FRANK G. HOLLAND.
